UNITED STATES PATENT OFFICE.

HENRY C. LOEVENHART, OF LEXINGTON, KENTUCKY, ASSIGNOR, BY DIRECT AND MESNE ASSIGNMENTS, OF ONE-HALF TO JACOB H. LOEVENHART, OF SAME PLACE.

BEDSTEAD ATTACHMENT.

SPECIFICATION forming part of Letters Patent No. 511,340, dated December 26, 1893.

Application filed March 16, 1893. Serial No. 466,317. (No model.)

To all whom it may concern:

Be it known that I, HENRY C. LOEVENHART, a citizen of the United States, and a resident of Lexington, in the county of Fayette and State 5 of Kentucky, have invented certain new and useful Improvements in Bedstead Attachments; and I do hereby declare that the following is a full, clear, and exact description of the invention, which will enable others skilled 10 in the art to which it appertains to make and use the same, reference being had to the accompanying drawings, which form a part of this specification.

My invention relates to improvements in 15 swinging brackets adapted to be pivoted to the end boards of a bedstead, for holding or supporting a chamber or spittoon; the construction and arrangement being such that the chamber or spittoon can be pushed underneath the bed, out of sight, when not in 20 use, and be readily swung outwardly, clear of the side-rails, when it is desired to use the same.

The invention consists in the novel construction and combination of parts hereinabove 25 fully described and claimed.

In the accompanying drawings: Figure 1 is 30 a side view of a bedstead with my improved bracket applied thereto. Fig. 2 is a detail perspective view.

Like numerals of reference denote corresponding parts in both figures.

In the said drawings, the reference numeral 1 designates the end boards, 2 the side rails, 35 and 3 the slats of a bedstead, which may be of any ordinary or usual construction. The bracket, which is preferably made of cast metal, comprises a straight bar or rod 4, having one end formed with a short downwardly 40 extending stud, 5, which is journaled or pivoted in lugs 6, secured to either or both of the end boards near the lower inner edges thereof; an outwardly extending segmental arm 7, having its end formed with a finger-hold 8, and 45 a short downwardly extending arm 9, with which is formed or connected a spittoon or chamber-holder, 10 or 12. The arm 7 passes through and engages with a recess 13, in a bar 14, secured to the side rail in the inner side 50 thereof.

The spittoon holder consists of an annular

ring or rim, of a size sufficient to allow the body of an ordinary spittoon or cuspidor, 15, to pass therethrough, but not large enough for the passage of the flaring mouth or upper 55 end thereof, whereby the cuspidor will be held by said flaring end engaging with the ring or rim, as seen in Fig. 1.

The chamber holder consists of a cup shaped receptacle, cut away at 16, and also having a 60 central opening in its bottom for the purpose of reducing weight. Its upper edge is formed with a recess 17 to receive the handle 18, of a chamber 19, which is shown inserted into the holder, in the side elevation Fig. 1. 65

In practice, I prefer to employ a spittoon holder at one end of the bedstead and a chamber holder at the other end, although both the spittoon-holder and the chamber-holder may be connected with either of the end-boards. 70

The operation will be readily understood. When it is desired to use the spittoon or chamber, the bracket is pulled out by means of the finger hold 8, the segmental arm 7 sliding upon the reduced or recessed portion of the 75 bar 14, and the spittoon or chamber swung clear of the bed. It will be noted that the weight of the bracket is supported by the arm 7 and the bar 14, thus taking the greater part 80 of the strain off the pivot. The said finger-hold acts also as a stop to limit the inward movement of the bracket by striking against bar 14.

Having thus described my invention, what I claim is— 85

The combination with a bedstead, of the bracket comprising the bar pivoted to the end board, the segmental arm having a finger-hold, the short downwardly projecting arm and the cup shaped chamber holder having a 90 recess in its edge, and the slotted bar secured to the side rail with which the segmental arm engages, substantially as and for the purpose specified.

In testimony that I claim the foregoing as 95 my own I have hereunto affixed my signature in presence of two witnesses.

HENRY C. LOEVENHART.
